ATTORNEYS

UNITED STATES PATENT OFFICE

HANNAH WENALAN, OF HIGHLAND PARK, ILLINOIS

CHOPPER

Application filed March 26, 1928. Serial No. 264,855.

My invention relates to improvements in choppers, and it consists in the combinations, constructions, and arrangements herein described and claimed.

5 An object of my invention is to provide a chopper which has novel means for receiving blades and holding the blades at desired positions when in use.

A further object of my invention is to 10 provide a device of the type described which is especially adapted to receive razor blades and is so constructed that the blades can readily be removed and new blades inserted in place.

15 Other objects and advantages will appear in the following specification, and the novel features of the invention will be particularly pointed out in the appended claim.

My invention is illustrated in the accompanying drawings, forming part of this application, in which

Figure 1 is a side elevation of my device,

Figure 2 is an end elevation of my device, and

25 Figure 3 is an enlarged detail view of a portion of my device.

In carrying out my invention, I provide a body portion or frame 1 which has its ends extending downwardly as at 2 and 3 and 30 provided with retaining flanges 4 and 5, respectively. U-shaped retaining members 6, 7 and 8 are provided with transversely extending portions 9 at each side thereof which are provided with integral retaining flanges 10.

25 The retaining members 6, 7 and 8 are substantially U-shaped in cross section and are rigidly secured to the frame or body portion 1 at spaced-apart positions by means of rivets 11 or the like. The U-shaped members 40 are also spaced apart a desired distance to provide elongated slots or recesses 12 for receiving razor blades 13 having reinforcing members 14.

An upright 15 is secured to the frame 1 by any suitable means, such as a screw 16. A handle 17 is pivotally mounted upon the upright 15 by means of a bolt 18 and a wing nut 19 and may be locked in any desired position.

50 From the foregoing description of the

various parts of the device, the operation thereof may be readily understood. It is obvious that the handle 17 may be moved in any desired position and locked in this position by tightening the wing nut 19 upon the bolt 18. The device may be readily actuated in any desired position, and with the razor blades inserted in place sharp edges are provided for chopping vegetables or the like.

It is true that the device is designed to employ razor blades of a specific type. However, cutting blades, as these might be termed, may be provided. The blades are frictionally held in place between the transversely extending portions 2, 3 and 9 and are held against displacement by the retaining flanges. If one of the blades should be broken, the user may readily draw the broken blade from the device and insert a new blade. Furthermore, any desired number of blades 65 may be used without departing from the spirit and scope of the invention. As, for instance, the user may remove all except one blade and use the device for some special purpose. The user may also use just two blades 70 or any number of blades. To accomplish this result, the blades desired to be used will be retained in the device and the remaining blades may be removed.

I claim:

A chopper comprising a handle having a sheet of material disposed adjacent one end thereof, said sheet of material being provided with flanges, a plurality of substantially U-shaped members disposed adjacent one side of the sheet of material, a plurality of blades disposed between the sides of certain of the U-shaped members and between other sides of said U-shaped members and said flanges, and means for securing said sheet of material and the U-shaped members to said handle.

Signed at Chicago, in the county of Cook, and State of Illinois, this 21st day of March, A. D. 1928.

HANNAH WENALAN.
